United States Patent Office.

ISAAC CAREY, OF MORRISTOWN, NEW JERSEY.

Letters Patent No. 102,773, dated May 10, 1870.

IMPROVEMENT IN FAUCETS.

The Schedule referred to in these Letters Patent and making part of the same.

To all whom it may concern:

Be it known that I, ISAAC CAREY, of Morristown, in the county of Morris and State of New Jersey, have invented a new and improved Compress Faucet; and I do hereby declare that the following is a full, clear, and exact description of the same, reference being had to the accompanying drawings, and to the letters of reference marked thereon making a part of this specification.

This invention relates to a new and improved compress faucet, in which the valve is kept in a closed state by means of a cam.

The object of the invention is to obtain a faucet which may be economically constructed and not be materially affected by wear, all screws being avoided in connection with the operating parts, so that the ordinary difficulty of the cutting away of the same by sand, which is contained in greater or lesser quantity in most water, cannot occur.

The invention is more especially designed to be applied to the supply-pipes of water-meters, but may be advantageously used in all cases where either a continuous or intermittent flow of water is required, and also where the supply or flow requires to be varied in volume.

In the accompanying sheet of drawings—

Figure 1 is an elevation of my invention.

Figure 2, a vertical central section of the same.

Figure 3, a plan or top view of the same with the cap removed.

Figure 4, a detached perspective view of the cam.

Similar letters of reference indicate corresponding parts in the several figures.

To enable those skilled in the art to fully understand and construct my invention, I will proceed to describe it.

A represents the shell of the faucet, the main portion *a* of which may be of cylindrical form, and the lower portion *b* of inverted conical form.

B is the eduction or discharge-tube, and

C, the induction-tube.

Within the upper portion *a* of the shell A there is permanently fixed or secured a cylindrical chamber, D, somewhat less in diameter than A, to admit of spaces or water-passages *c c* between them, and these passages communicate with the eduction or discharge-tube B, (see fig. 2).

The induction-tube C passes through the part *a* of the shell A, and communicates with the chamber D, as shown clearly in fig. 2.

Within the chamber D there is a fixed cylindrical stem, E, having a central position within the chamber, and extending upward some distance above the top of the shell A.

The portion *d* of this stem within the chamber is

of greater diameter than the portion *e* above said chamber, but a space, *f*, is allowed all around between the stem and the inner surface of the chamber, (see figs. 2 and 3).

F is a valve, composed of two parts, *g* and *h*; the former, *g*, being constructed of India rubber, leather, or other suitable elastic or flexible material, the latter, *h*, being of metal, and allowed to rise and fall freely between guides *i i* at the inner side of the shell A.

G is a cap, fitted on the top of the shell A, and having the upper part *e* of the stem passing centrally through it, the cap being allowed to turn freely on *e* as a center.

The under side of the cap has a cam, H, attached to, formed, or cast with it in one piece.

This cam may be described as being of cylindrical shape, with its lower edge hollowed out at opposite sides to form two prominent projecting parts, *j j*, as shown in figs. 2 and 4.

The valve F is held down upon the top of the chamber D by the cam H, when the cap G is so turned that the prominent pendent parts *j j* bear upon the metallic part *h* of the valve, as shown in fig. 2; and when the cap C is turned so that said prominent parts will be more or less off from the part *h* of the valve, the latter will rise under the pressure of the water, and the water pass through the induction-tube C into chamber D, and up out of the top thereof, and thence down through the passages *c c* into and out from the eduction-tube B, as indicated by the arrows in fig. 2.

A very slight movement or turn of the cap C will close the valve and admit of its opening, and the flow or discharge of water is regulated by turning the cap more or less.

By this arrangement it will be seen that there are no parts liable to become deranged by use.

The cap is held in position by a screw-nut, *k*, and washer, *l*, on a screw, *m*, cut on the upper part of the stem E, which passes through the center of the cap, the latter working on the stem as a center, a washer, *l*, being necessary to prevent leakage around the stem through the cap.

It is designed to have the portion of the cap that rests on the top of the shell A, and also the latter, ground, or made as smooth as possible, in order to prevent leakage between the cap and shell.

The cap may be turned by having its edge serrated or milled, to prevent the slipping of the hand upon it, or by having a suitable handle attached to it.

I would remark that, in lieu of the stem E, a flange may be screwed on the top of the shell A, and so arranged as to extend all around over the top of the cap, and retain the latter in proper position, and at the same time admit of it being turned. I prefer,

however, the stem to effect that result, as being the least expensive.

Having thus described my invention, What I claim as new, and desire to secure by Letters Patent, is—

The cap G, with the cam H attached, in combination with the valve F, chamber D, shell A, induction

and eduction-tubes C B, and the water-passages c c, all constructed and arranged substantially as and for the purpose set forth.

ISAAC CAREY.
